C. H. HOFRICHTER

LIGHTING FIXTURE

Filed March 7, 1922

UNITED STATES PATENT OFFICE.

CHARLES H. HOFRICHTER, OF CLEVELAND, OHIO, ASSIGNOR TO THE CRESCENT BRASS PRODUCTS COMPANY, OF CLEVELAND, OHIO, A CORPORATION OF OHIO.

LIGHTING FIXTURE.

Application filed March 7, 1922. Serial No. 541,657.

To all whom it may concern:

Be it known that I, CHARLES H. HOFRICHTER, a citizen of the United States, and a resident of Cleveland, county of Cuyahoga, 5 and State of Ohio, have invented a new and useful Improvement in Lighting Fixtures, of which the following is a specification, the principle of the invention being herein explained, and the best mode in which I have 10 contemplated applying that principle so as to distinguish it from other inventions.

The present invention relates to lighting fixtures having an adjustable socket, and more particularly, the invention relates to 15 the means for adjusting the socket along the axis of the fixture and for readily and easily making such adjustment without disturbing the wiring, lamp or globe. To the accomplishment of the foregoing and related ends, 20 said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

30 Fig. 1 is an elevational view of the adjusting device with the reflector shown in section.

Fig. 2 is a section on line 2—2 of Fig. 1 with parts broken away and with parts 35 shown in elevation.

Fig. 3 is a section on line 3—3 of Fig. 1.

Fig. 4 is a section on line 4—4 of Fig. 1.

As shown, the present fixture consists of a metallic shell or shade-holding member 1 40 of general conical shape which is provided with an eye 2 for attachment to the ceiling or the like. A reflector or shade 1^a is attached to the lower end of member 1, in any suitable manner and the upper end 3 of 45 said member is flattened and has apertures 4 and 5 therein. Secured in apertures 4, which are two in member, are two rods 6 disposed parallel with the axis of the member which are held in place by means of nuts

7, these rods being diametrically opposite 50 each other. Mounted within member 1 is a socket 9 of usual construction adapted to receive the lamp bulb 10, this socket being provided with two apertured ears 11 adapted to receive the rods 6 and act as guides 55 for the socket.

In order to adjust the socket and thus the bulb, in and out with respect to member 1 and reflector 1^a, a threaded adjusting screw 12 is mounted through the aperture 5 in the 60 member, the screw having a knob 20 at its outer end by which it can easily be turned. This screw engages in an interiorly threaded block 13 formed on a strap 15 adapted to encircle the socket and clamped thereon by 65 means of a screw 16 and nut 17 received in apertures 18 in the bent ends of the strap.

The position of the socket may readily be changed by turning the knob 20 which moves the block 13 in and out along the 70 screw, the rods 6 acting as guides to hold the socket in alignment and against rotation, the position of the bulb relative to the member 1 or fixture and to any shade or globe which may be attached thereto being 75 readily changed so that the light filament may be correctly positioned.

The construction is simple and inexpensive and may be readily assembled. The adjustment is simple and the parts are relatively strong and reliable to breakage. A wide range of alignment may be made and thus bulbs of many types may be used with maximum efficiency from each.

Other modes of applying the principle of 85 my invention may be employed instead of the one explained, change being made as regards the mechanism herein disclosed, provided the means stated by the following claim or the equivalent of such stated means 90 be employed.

I therefore particularly point out and distinctively claim as my invention:—

In a lighting fixture, the combination of 95 a metallic holder adapted to carry the globe, and provided at its upper end with a flat top having three apertures, guide rods rigidly mounted in two of such apertures and

- extending parallel to the axis of said holder, a threaded adjusting screw rotatably mounted in such third aperture and provided above said top with a knob, a lamp socket 5 having two apertured ears slidably mounted on said rods, a removable band clamped about said socket and provided with a block

having a threaded aperture adapted to receive said adjusting screw to move said socket along said rods upon rotation of said screw. 10

Signed by me, this 15 day of February, 1922.

CHARLES H. HOFRICHTER.
